Primary Examiner — Thomas Johannes*Assistant Examiner* — Catherine Posthauer(74) *Attorney, Agent, or Firm* — Cantor Colburn LLP(57) **CLAIM**

The ornamental design for a lid, as shown and described.

DESCRIPTION

FIG. 1 is a perspective view of an embodiment of a lid showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof, in a condition of use forming no part of the claim.

The broken lines are shown for the purpose of illustrating subject matter and parts of the lid that form no part of the claimed design.

1 Claim, 8 Drawing Sheets(56)
